(57)

CLAIM

The ornamental design for a biological cell processing chip, as shown and described.

DESCRIPTION

FIG. 1 is an isometric view of a biological cell processing chip in accordance with our new design; FIG. 2 is a front elevation view thereof; FIG. 3 is a rear elevation view thereof; FIG. 4 is a right side elevation view thereof; FIG. 5 is a left side elevation view thereof; FIG. 6 is a top plan view thereof; FIG. 7 is a bottom plan view thereof; FIG. 8 is an isometric view of the biological cell processing chip of FIGS. 1-7 in a state of use; FIG. 9 is an isometric view of another embodiment of a biological cell processing chip in accordance with our new design;

FIG. 10 is a front elevation view thereof; FIG. 11 is a rear elevation view thereof; FIG. 12 is a right side elevation view thereof; FIG. 13 is a left side elevation view thereof; FIG. 14 is a top plan view thereof; FIG. 15 is a bottom plan view thereof; and, FIG. 16 is an isometric view of the biological cell processing chip of FIGS. 9-15 in a state of use.

The broken lines in FIGS. 1-7 and 9-15, the areas within them, and the unshaded areas bounded by broken lines and solid lines depict portions of the biological cell processing chip that form no part of the claimed design. The additional

(Continued)

broken lines shown in FIGS. 8 and 16 depict environmental subject matter and form no part of the claimed design.

1 Claim, 10 Drawing Sheets
